CONTROL LEVER

James Edward Bartrug, Webster City, Iowa

Application November 10, 1948, Serial No. 59,214

7 Claims. (Cl. 74—531)

1

The principal object of my invention is to provide a means for adjustably holding a reciprocating rod, shaft or like against accidental or objectionable longitudinal movement.

More specifically, the object of this invention is to provide a strong manually operated lever for controlling the reciprocating movement of carburetor throttle rods of tractors and like machinery where the control rod is subject to displacement by vibration.

A still further object of my invention is to provide a carburetor throttle lever that is capable of extremely fine adjustment.

A still further object of my invention is to provide a control lever that is easy to release and operate.

A still further object of my invention is to provide a manually controlled lever that is economical in manufacture and durable in use.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a side view of my device installed and in use.

Fig. 2 is a longitudinal sectional view of the device taken on line 2—2 of Fig. 1.

Fig. 3 is a cross-sectional view of my control lever taken on line 3—3 of Fig. 1.

Control levers are old and found in most all types of machinery. Also all internal combustion engines have some manually operated means for controlling the carburetor setting. In the case of tractors this means usually is a rod of the "push and pull" type. Such means is most unsatisfactory because the vibration and movement of the tractor makes fine manual adjustment almost impossible. Furthermore, the movement of the tractor over uneven ground, and the vibration of the engine tends to change the position of the throttle rod after it has been adjusted. Some attempt has been made to overcome this latter problem by providing holding notches, but the objection to notches is that fine adjustment is impossible. I have overcome such troubles by providing an easily operated, accurate and stable lever control which I will now describe.

The numeral 10 designates any suitable portion of a tractor frame or like to which my control may be secured by a bolt or like 11. The man-

2

ner of attaching or place is not important to this invention provided it is in a convenient location relative to the operator and in line with the carburetor throttle control rod 12. The numeral 13 designates the horizontal extending base strap portion secured at its forward end by the bolt 11 to the tractor frame or like. Extending above and from the center portion of this base strap is the segment 14. This circular extending portion 14 is flat when viewed from the rear or front and is similar to the strap base 13. It extends in approximately one hundred and eighty degrees of arc, as shown in Fig. 1. The numeral 15 designates a strap handle pivoted near its lower end to the center of the base strap by a bolt, rivet, or like 16, as shown in Fig. 2. This strap extends upwardly from the left side of the base 13, along the left side of the portion 14 and then beyond the portion 14 to form the grip portion 17. Holes 18 are provided in the lower end portion of the strap handle and below the base strap 13 for selectively receiving the end of the throttle rod 12. These holes provide selection of greater or less stroke of the rod 12 relative to the handle strap 15 and likewise greater or less leverage. An auxiliary strap 19 may be secured along the left side of the strap handle to provide a carburetor handle to provide a carburetor throttle rod receiving hole 20 above the pivot point of the handle strap if desired. This may sometimes be preferred in certain situations, and when used the movement of the rod 12 will be reversed relative to the movement of the lower end of the handle strap. The numeral 21 designates a friction bar pivoted at its lower end on the bolt 16. This bar extends upwardly from the right side of the base strap and along and past the right side of the portion 14, as shown in Fig. 2. By this arrangement the member 15 and member 21 extend at each side of the portion 14, respectively. They are held together in parallel relationship by the two elongated bolts 22 and 23. The bolt 22 is within the arc of the portion 14 and the bolt 23 is beyond the arc of the portion 14. Besides the two portions 14 and 21, the two bolts also loosely extend through a guard member 24. This guard member is to the left of the strap handle 15. The numeral 25 designates a heavy coil spring between the guard 24 and the strap handle 15. As the bolts limit the movement of the guard member 24 to the left and the bar 21 to the right, this coil spring will yieldingly hold the strap handle and the bar toward each other, thereby tightly clamping the arc portion 14 between them. The left and right

sides of the portion 14, and the right side of the strap handle and the left side of the bar 21 will provide the powerful clutch faces of my device. The numeral 26 designates a bearing shield portion on the strap handle and beyond the bolt 23. The numeral 27 designates a pin slidably extending through the handle strap, having its right end engaging the upper left side portion of the bar 21, and its left end extending into the bearing shield portion 26, as shown in Fig. 2. The numeral 28 designates a curved lever having its end pivoted in the member 26 and engaging the left end of the pin beyond its pivot point. The numeral 29 designates a handle lever pivoted in the member 26 and engaging the free end of the lever 28 beyond its pivot point. This compound leverage makes the release of the clutch phase of my device manually easy. The numeral 30 designates a light expansion spring having one end bearing on the member 24 and its other end bearing on the handle lever 29 for normally holding it in engagement with the lever 28 and the lever 28 in engagement with the pin 27. By manually bringing the handle 29 and grip 17 toward each other, the lever 28 will be moved to the right, thereby moving the pin 27 to the right and spreading the handle strap 15 and bar 21 away from each other and out of gripping contact with the side faces of the portion 14, as shown by dotted lines in Fig. 2. With the strap handle member and the bar 21 spread apart against the powerful action of the spring 25, the segment 14 will be free relative to the handle strap 15 and the handle unit may be moved forwardly or backwardly to actuate the throttle rod 12, as shown by dotted lines in Fig. 1. Any desired position of the handle unit may be had as no limiting notches are present. As soon as the desired fine adjustment is obtained, it is merely necessary to release pressure on the lever 29 to permit the pin 27 to move to the left, permitting the strong spring 25 to pull the members 15 and 21 together and clamp them on the portion 14. With the members 15 and 21 rigidly clamping onto the portion 14, the throttle rod will be rigidly and permanently held in the desired position until it is desired to change it. This strong holding of the strap handle in the selected position will not be affected by vibration or movement of the tractor. As any wear would have to be on the wide sides of the segment 14 or wide sides of the members 15 and 21, the device will last almost indefinitely. In fact these portions could be worn relatively thin without affecting the proper functioning of the device. The desired clutch tension may be adjustably obtained by tightening or loosening the bolts 22 and 23. Although I have described my device for easy use in connection with carburetor control rods, it is obvious that it may be used wherever an accurate, fine adjustment of a rod member is desired, and such an adjustment after attainment must be maintained under all conditions.

Some changes may be made in the construction and arrangement of my control lever without departing from the real spirit and purpose of my invention, and it is my intention to cover by my claims, any modified forms of structure or use of mechanical equivalents which may be reasonably included within their scope.

I claim:

1. In a device of the class described, a supporting member, a base strap portion secured to said support member, a flat circular member extending above said base strap portion and having its

two ends integrally formed to said base strap portion, a strap lever having its lower portion pivoted to said base strap portion and extending upwardly adjacent one side of said flat circular member, a bar member pivoted at its lower end to said base strap portion and extending upwardly adjacent the other side of said flat circular member and parallel with said strap lever, a spring retaining member, a bolt extending through said strap lever, said bar member, and said retaining member, a coil spring between said spring retaining member and said strap lever, and a handle means for spreading said strap lever and said bar member away from each other and against the action of said coil spring at times.

2. In a device of the class described, a supporting member, a base portion secured to said support member, a flat circular member extending above said base portion and having its two ends integrally formed to said base portion, a lever having its lower portion pivoted to said base portion and extending upwardly adjacent one side of said flat circular member, a bar member pivoted at its lower end to said base portion and extending upwardly adjacent the other side of said flat circular member and parallel with said lever, a spring retaining member, a bolt extending through said lever, said bar member, and said retaining member, a coil spring between said spring retaining member and said lever, and a handle means for spreading said lever and said bar member away from each other and against the action of said coil spring at times.

3. In a device of the class described, a supporting member, a base strap portion secured to said support member, a flat circular member extending above said base strap portion and having its two ends integrally formed to said base strap portion, a strap lever having its lower portion pivoted to said base strap portion and extending upwardly adjacent one side of said flat circular member, a bar member pivoted at its lower end to said base strap portion and extending upwardly adjacent the other side of said flat circular member and parallel with said strap lever, a spring retaining member, a bolt extending through said strap lever, said bar member, and said retaining member, a coil spring between said spring retaining member and said strap lever, and a handle means for spreading said strap lever and said bar member away from each other and against the action of said coil spring at times.

4. In a device of the class described, a supporting member, a base strap portion secured to said support member, a flat circular member extending above said base strap portion and having its two ends integrally formed to said base strap portion, a strap lever having its lower portion pivoted to said base strap portion and extending upwardly adjacent one side of said flat circular member, a bar member pivoted at its lower end to said base strap portion and extending upwardly adjacent the other side of said flat circular member and parallel with said strap lever, a spring retaining member, a bolt extending through said strap lever, said bar member, and said retaining member, a coil spring between said spring retaining member and said strap lever, a pin slidably extending through said strap lever and having one end bearing on the inner side of said bar member, a means for securing a control rod to said strap lever, and a manually operated cam means bearing on the other end of said pin and operatively secured to said strap lever.

5. In a device of the class described, a support-

ing member, a base strap portion secured to said support member, a flat circular member extending above said base strap portion and having its two ends integrally formed to said base strap portion, a strap lever having its lower portion pivoted to said base strap portion and extending upwardly adjacent one side of said flat circular member, a bar member pivoted at its lower end to said base strap portion and extending upwardly adjacent the other side of said flat circular member and parallel with said strap lever, a spring retaining member, a bolt extending through said strap lever, said bar member, and said retaining member, a coil spring between said spring retaining member and said strap lever, a pin slidably extending through said strap lever and having one end bearing on the inner side of said bar member, a means for securing a control rod to said strap lever, and a manually operated compound cam means bearing on the other end of said pin and operatively secured to said strap lever.

6. In a device of the class described, a supporting member, a base strap portion secured to said support member, a flat circular member extending above said base strap portion and having its two ends integrally formed to said base strap portion, a strap lever having its lower portion pivoted to said base strap portion and extending upwardly adjacent one side of said flat circular member, a bar member pivoted at its lower end to said base strap portion and extending upwardly adjacent the other side of said flat circular member and parallel with said strap lever, a spring retaining member, a bolt extending through said strap lever, said bar member, and said retaining member, a coil spring between said spring retaining member and said strap lever, a pin slidably extending through said strap lever and having one end bearing on the inner side of said bar member, a means for securing a control rod to said strap lever, a bearing on said strap

lever, a lever pivoted at one end to said bearing and engaging the other end of said pin beyond its pivot point, a second lever pivoted at one end to said bearing and engaging the free end of said first lever at a point beyond its pivot point, and a spring means for yieldingly holding said second lever in normal operative position.

7. In a device of the class described, a member designed to be secured to a support and having a base strap portion and a flat circular portion extending above it, a strap lever having its lower portion pivoted to said base strap portion and extending past and adjacent one side of said flat circular portion, a bar member pivoted at its lower end to said base strap portion and extending past and adjacent the other side of said flat circular portion and parallel with said strap lever, a spring retaining member, a bolt extending through said strap lever, said bar member, and said retaining member, a coil spring between said spring retaining member and said strap lever, and a handle means for spreading said strap lever and said bar member away from each other and against the action of said coil spring at times.
